Primary Examiner—B. J. Bullock[57] **CLAIM**

The ornamental design for a television set top decoder box, as shown and described.

DESCRIPTION

FIG. 1 is a perspective view of a television set top box decoder showing my new design;
FIG. 2 is a front elevational view thereof;
FIG. 3 is a top plan view thereof; and,
FIG. 4 is a right side elevational view thereof.
Those details shown in phantom—broken lines—are intended to indicate environmental aspects and are not part of the claimed design.
